UNITED STATES PATENT OFFICE.

GEORGE W. MILLS, JR., OF BROOKLYN, NEW YORK.

NECKWEAR.

1,273,262.

Specification of Letters Patent. Patented July 23, 1918.

Application filed March 18, 1915. Serial No. 15,179.

To all whom it may concern:

Be it known that I, GEORGE W. MILLS, Jr., a citizen of the United States, and a resident of the borough of Brooklyn, county of Kings, 5 and State of New York, have invented certain new and useful Improvements in Neckwear, of which the following is a specification.

My invention relates to neckwear of the 10 type wherein the wearer forms the bow or knot, such as is commonly known as four-in-hands, bow-ties, ascots, etc., and particularly of that specific type wherein the tie is made by cutting the goods from the piece 15 and folding to form the neckwear. The object of my invention is to provide neckwear in which the material of the cover fabric does not extend all the way across the underside or inner face of the tie, and in 20 which a suitable material is used on the inner face or underside of the tie in place of the cover fabric. In other words, I provide a form of lined neckwear.

My invention also provides for neckwear 25 in which the intermediate portion or the neckband portion, in whole or in part, is of the minimum thickness—that is, it is as thin as it is possible to make it without mutilating or destroying the appearance of the tie.

30 I also provide means for preventing the displacement of the interlining within the neckwear, and also provide means for reinforcing the neckwear throughout its length, which is particularly of advantage when the 35 cover fabric is cut on the bias. My improved neckwear in the preferred form is economical to manufacture, while affording all the advantages referred to above.

In the drawings in which like letters refer 40 to like parts,

Figure 1 is a view of the inner face of a completed necktie;

Fig. 2 is a longitudinal section taken through Fig. 1;

45 Fig. 3 is a cross-section on line 3—3, Fig. 1;

Fig. 4 is a cross-section on line 4—4, Fig. 1;

50 Figs. 5, 6, 7, 8 and 9 show modifications of my invention, Fig. 5 showing several parts of a necktie assembled; Fig. 6 showing the inner face of one form of my invention;

Fig. 8 showing another modification of which Fig. 7 is a longitudinal section on the 55 line 6—6, and Fig. 9 being a cross-section of Fig. 8 on the line 4—4; and

Fig. 10 is a cross-section of Fig. 8 on the line 5—5.

In the drawings, the preferred form of my invention shown in Figs. 1, 2, 3 and 4, A represents the cover fabric which is cut from piece goods and may be made of several pieces attached to each other, as is commonly done in the manufacture of neckwear. D—D shown in Fig. 2 are interlinings of 65 canton flannel or suitable material, which I prefer to make independent of each other, and place in the tying ends only. The ends of the interlinings are shown in Fig. 1 by the dotted lines D'—D'.

J is a reinforcing lining material which extends throughout the length of the neckband and substantially the length of the tying ends. This reinforcing lining J also serves for the back or underside of the necktie covering or bridging over the space between the edges of the folded cover fabric A, as shown in Figs. 3 and 4. In the preferred form of my invention I prefer to make this of a ribbon or ribbon-like material 80 in which the longitudinal edges are so finished that they need not be folded under as would be the case with piece goods. This use of ribbon or ribbon-like material with selvage edges gives a lining reinforcing material of great strength and enables the same to be sewed down upon the cover fabric without folding the edges under thereby obviating the necessity of increasing the thickness along the edges. By using this reinforcing lining strip J, I am enabled to save a considerable portion of the cover fabric A, which is, of course, the most expensive material used in the manufacture of neckwear, as it is not necessary to have any material 85 under the reinforcing lining strip J.

The reinforcing lining J, I prefer to have stitched throughout the neckband portion, or a substantial part thereof, by rows of stitches M which pass through not only the 100 reinforcing lining J, but also through the cover fabric as shown in Fig. 4—that is, the stitches M pass through the outer face of the cover fabric, the edge of the cover fabric which is folded over, and the longitudinal 105 edge of the reinforcing lining J. At the ends the stitches M extend cross-wise of the neckwear, as shown in Fig. 1, so as to engage with the inner ends of the interlinings D. This is clearly shown in Fig. 1 where 110 D' represents the inner end of the interlinings, and the stitches M are shown beyond

the ends of said interlinings. Throughout the balance of the length of the reinforcing lining strip J, I stitch the lining strip J to the cover fabric by rows of stitches L 5 which may, if desired, pass through the reinforcing lining J, the edges of the cover fabric A, and engage with the interlining D, as shown in Fig. 3.

In addition, I also provide rows of 10 stitches E—E which I prefer to have extend along near the edges of the tying ends, as shown in Figs. 1 and 3, which stitches engage with the inner face of the cover fabric near the edges and also engage with the 15 edges of the interlining so as to hold the interlining against displacement, while, at the same time, assisting to reinforce the cover fabric, which is particularly advantageous when the cover fabric is cut on the 20 bias. The nearer the edge of the inner face the rows of stitches E—E are placed the greater the reinforcement of the cover material.

I have found that the rows of stitches 25 E—E can be placed upon the inner face of the tie after the tie is all assembled, as shown in Fig. 1, by using what is known as a blind stitching machine. In fact all of the 30 rows of stitches L—L and E—E may be made in the manufacture of my neckwear by this blind stitching machine, and the rows of stitches M also could be made that way when it is desired only to have the stitches 35 pass through the reinforcing lining J and the folded edges of the cover fabric, but for the purposes of strength I prefer to have the stitches M made with the ordinary machine, in which the stitches pass through the plies in the neckband, and preferably a 40 lock-stitch machine.

In a necktie made as shown in Figs. 1, 2, 3 and 4, and described above, it will be noted that the fabric of the cover material A when cut on the bias is reinforced 45 throughout its length by the reinforcing lining J, which is cut on the straight, and preferably of a ribbon, or ribbon-like material having longitudinal selvage edges. It will also be noted that the neckband is of 50 the minimum thickness—that is, it is as thin as it can be made without destroying the appearance of the neckwear. The outer face of neckwear manufactured as shown and described above will have the same 55 appearance as the ordinary neckwear on the market, and will be adapted for wearing with the two-fold collar, or with the ordinary stand-up collar. In this necktie, when being tied or adjusted, the strain will 60 all be carried by the reinforcing lining J, and will be assisted by the interlining D, through the medium of the stitches E—E. The neckband being very thin—only two 65 plies of material—will slide back and forth between the plies of a two-ply collar. Such

a tie is economical to manufacture because it dispenses with the thin bridge piece in the neckband, such as is shown in Fig. 5. It dispenses with the assembling of an interlining, such as shown in Fig. 5. It saves a 70 substantial amount of the expensive cover fabric by reason of the fact that it is not necessary to have the cover fabric extend clear across the inner face of the tie, and then folded under where the two edges 75 meet, as is the ordinary way of manufacturing neckwear of the flowing-end type; or of the folded type of tie without the flowing ends.

Practically all of the rows of stitches can 80 be done on a machine, whereas, heretofore it has been usual to have blind stitches made by hand in this art, and this tie has all of the advantages described in the forepart of this specification.

In Figs. 5 and 6 I have shown a modification of my invention in which the reinforcing lining J is cut from piece goods and stitched to the cover fabric, preferably by turning the fabrics, stitching them on the 90 wrong side, and then turning them and placing the stitching E—E longitudinally of the neckwear, as described above. This stitching engages with the reinforcing lining J and with the interlining, and the two 95 outer rows of stitches E—E engage with the edge of the folded cover fabric A and the interlinings D—D.

I have shown in Fig. 5 the interlinings 100 D—D connected with a bridge B by the rows of stitches C—C. This is the ordinary interlining in use in this art, and while I have shown it for illustrative purposes, I prefer not to use the strip B as it is unnecessary when the reinforcing lining strip J, 105 which extends throughout the neckband and the tying ends of the neckwear and carries substantially all of the strain, is used. In this form of neckwear it will be noted that the reinforcing lining J cut on the straight 110 is wider in the tying ends than in the intermediate portion. If desired, of course, it could be made the same width throughout, but the wider it is in the tying ends, the more cover fabric A may be saved.

This construction is, of course, suitable to the flowing-end necktie shown in Fig. 1, as well as the form of necktie shown in Fig. 6. In Fig. 8, I have shown a form of necktie substantially the same as Fig. 6, except that the cover fabric is folded over the inner face of the intermediate portion so that both the inner and outer faces of the intermediate portion of the necktie are of the same material. In this form of necktie the reinforcing lining strip J performs the function of a lining on the inner face of the tying ends and an interlining in the neckband.

Fig. 7 is a longitudinal section on the line 6—6 of Fig. 8. Fig. 9 shows a cross-section 130

of the tying ends of neckwear made as shown in Fig. 8; and Fig. 10 shows a cross-section of the neckband portion, showing how the cover fabric forms both the inner and outer 5 faces of the tying ends.

It will be noted that in none of the neckties made in accordance with my invention is there any seam intermediate the tying edges of the necktie made by bringing the 10 folded portions of the cover fabric A together so as to form the seam.

In making neckwear containing my invention I prefer to have the reinforcing lining always cut on the straight if cut from piece 15 goods, or, as in the preferred form, made from a ribbon-like material having selvage longitudinal edges so that the reinforcing lining J is practically unstretchable, and yet carry all of the strain put upon the necktie 20 without permitting the cover fabric, particularly when cut on the bias, to stretch.

Having described my invention, what I

claim as new and desire to secure by Letters Patent is:—

In a necktie having a neckband and two 25 tying ends, a bias-cut cover fabric forming the outer face of the tying ends, the edges of the cover fabric being folded back and being spaced apart for substantially the length of a tying end, an interlining for a 30 tying end, a straight-cut lining for a portion of the inner face of the tie, stitches securing said lining to said interlining substantially throughout the length of said lining, the said edges of said cover fabric being positioned between the edges of said interlining and said lining and additional stitches securing said lining to said edges of said cover fabric, said lining bridging the space between said edges and holding said interlining 35 in place.

In testimony whereof I have signed my name to this specification.

GEO. W. MILLS, JR.
